UNITED STATES PATENT OFFICE.

WILLIAM PRESTON HARTFORD AND CLARENCE MONROE RICKOFF, OF CHICAGO, ILLINOIS, ASSIGNORS, BY DIRECT AND MESNE ASSIGNMENTS, OF ONE-THIRD TO SAID HARTFORD, ONE-THIRD TO WILLIAM T. DARDEN, AND ONE-THIRD TO ANGUS P. MCPHERSON, OF CHICAGO, ILLINOIS.

COIN-HOLDER.

1,197,736.

Specification of Letters Patent. Patented Sept. 12, 1916.

Application filed August 21, 1915. Serial No. 46,690.

To all whom it may concern:

Be it known that we, WILLIAM PRESTON HARTFORD and CLARENCE MONROE RICKOFF, citizens of the United States, residing at 5 Chicago, in the county of Cook and State of Illinois, have invented, certain new and useful Improvements in Coin-Holders, of which the following is a specification.

This invention relates to new and useful 10 improvements in coin holders embodying therein an electrical display device, and the primary object of the invention is to provide an improved device of this character whereby upon coins being placed in the 15 holder an advertising medium is visualized in the face of a translucent mirror in said holder to attract attention to the same.

Another object of this invention is to provide a device of this character having a 20 translucent mirror normally reflective, and an advertising medium beneath the same adapted to be illuminated upon coins being placed in the holder so that the said advertising is visible in the mirror as long 25 as the coins remain in the holder.

Still another object of the invention is to provide a circuit control device in the coin receptacle to operate a lamp to illuminate the advertising medium for the purpose 30 stated.

A further object of the invention is to provide a device which is simple and durable in construction, inexpensive to manufacture, and one which will be very efficient in operation.

With these and numerous other objects in view, our invention consists in the novel features of construction, combination and arrangement of parts which will be herein 40 referred to and more particularly pointed out in the specification and claims.

In the drawings, Figure 1 is a perspective view of the device; Fig. 2 is a central vertical longitudinal section; Fig. 3 is a horizontal section taken substantially on line 45 3-3 of Fig. 2; Fig. 4 is a vertical transverse section on line 4-4 of Fig. 2.

In describing the invention we shall refer to the drawings, in which similar reference characters designate corresponding parts throughout the several views, and in which the numeral 1 designates a casing, which in this instance is shown as being

substantially rectangular in shape with an inclined or sloping top 2. We do not wish 55 to be limited to any particular shape of casing, but any shape or form that is most desirable and convenient for use may be utilized. The sloping top 2 of the casing has positioned in the upper portion of the 60 same and lying flush with its upper surface, a translucent mirror 3. The lower portion of said top is concaved as shown at 4, to form a receptacle to receive coins. In the bottom of said receptacle is placed a pair 65 of spaced contacts 5 and 6, which are formed preferably of metal, being semi-circular, and sunk in the lower portion of said receptacle.

The receptacle 1 has a removable base portion 7 which is held therein by any fastening means, for instance as shown at 8. This base portion 7 has projecting upwardly therefrom, intermediate its ends and disposed adjacent either side, a pair of supports 9 and 10, which have attaching feet on their lower end, and the upper portions of the same are bent at an angle upwardly and rearwardly to a point contiguous the upper surface of the casing. These supports are formed laterally U-shaped to form 75 a guide adapted to receive an indicia 11 which is spaced thereby below the mirror 3 and obliquely thereto with respect to the same. The indicia 11 in this instance is 80 meant to comprise any preferred form of advertising matter, such as a card having either printed matter or an image printed or portrayed thereon. It is held in the aforesaid position, at an angle to the mirror, for a purpose to be hereinafter described. Secured to the upper surface of the base 7, at a point in front of the said supports, is a substantially U-shaped reflector 12, which is secured to the said base at one side of the bent 90 portion, as shown at 13, so that the lower arm of the same is positioned in the same plane as the plane of the indicia 11 is supported in. Secured in the base portion of the reflector is a lamp 14, which is shown as 95 100 comprising a plurality of electric lamps which have their sockets secured to the said reflector and project therethrough. The projecting ends of the sockets are secured by a transversely extending bus bar 15.

The removable base 7 has fastened on its

upper surface adjacent the rear end of the same clamps 16 which are adapted to hold therebetween dry cells 17, constituting a battery, which are for the purpose of ordinarily giving the current necessary to operate this device.

One of the contacts 5, which is disposed in the receptacle 4, is connected with the bus board 15 by a wire 18, while the other contact 10 6 is connected by a wire 19 with one of the terminals of the batteries. A wire 20 connects the other terminals of the batteries with the reflector 13, so that upon bridging or connecting the said contacts a complete 15 circuit is formed and the lamps are lighted. If desired, the current may be brought from some outside source, as shown at 21.

The device is normally inoperative, but upon the placing of any conductors, such as 20 coins, in the receptacle 4, the same will slide to the bottom and form a contact between the contact points 5 and 6, thereby completing a circuit and lighting the lamps 14, as described. The light from the lamp will be 25 reflected on the indicia, or advertising matter 11, and owing to the positioning of the same, immediately upon its illumination, it is visualized through the translucent mirror 3. When the conductors are removed from 30 the receptacle, the circuit will be broken, the light extinguished, and the indicia will disappear from the mirror, leaving only the reflecting action of the same visible.

The device above described forms a very 35 novel and efficient display apparatus that is especially adaptable for use in stores, etc., where it may be placed upon the counter, and a clerk upon making change drops it in the coin receptacle in the holder, where- 40 by this device will be operated and the advertising matter displayed will undoubtedly attract the customer's attention, as he removes the change. The contacts 5 and 6 are placed so close together, or have a strip of 45 insulating material therebetween, so as to prevent coins dropping through the space between the two. The casing may be made of any material, or in any attractive shape, and if desired a cigar cutter, or the like, 50 may be placed thereon.

From the foregoing description of the construction of our improved device, the manner of applying the same to use and the operation thereof will be readily understood 55 and it will be seen that we have provided a simple, inexpensive and efficient means for carrying out the objects of the invention.

While we have particularly described the 60 elements best adapted to perform the functions set forth, it is obvious that various changes in form, proportion, and in the minor details of construction may be resorted to, within the scope of the appended claims, without departing from the spirit or sacri- 65 ficing any of the principles of the invention.

What is claimed is:—

1. In a coin holder, a translucent mirror normally reflective, an indicia, and means for illuminating said indicia upon the insertion of a coin in said holder, whereby the 70 indicia is visualized through the mirror.

2. In a coin holder, a translucent mirror normally reflective, an indicia disposed beneath said mirror, and circuit controlled means for illuminating said indicia upon 75 the insertion of a conductor in the holder whereby the indicia is visualized through the mirror.

3. A coin holder comprising a translucent mirror normally reflective, a pair of spaced contacts, an indicia, an electric lamp, a source of current, and connections between said source of current, lamp and contacts whereby the lamp is operated upon the bridging of said contacts by the insertion 85 of a coin in the holder.

4. A coin holder comprising a casing having a translucent mirror and a receptacle, an indicia disposed beneath said mirror and an electric lamp disposed adjacent thereto in said casing, and circuit controlled means in said receptacle to operate the lamp.

5. A coin holder comprising a casing, a translucent mirror disposed in a portion of the top of said casing, a concave receptacle in the remaining portion of said top, an indicia disposed in said casing beneath the mirror at an angle to the same, an electric lamp therein in front of the indicia, and circuit controlled means in the bottom 100 of said receptacle to operate the lamp.

6. A coin holder comprising a casing, a translucent mirror disposed in a portion of the top of said casing, a concave receptacle in the remaining portion of said top, an indicia supported in said casing beneath the mirror and obliquely with respect thereto, an electric lamp in front of said indicia, a reflector for said lamp, and circuit controlled means in the bottom of said receptacle to operate said lamp.

7. A coin receptacle comprising a casing, a translucent mirror disposed in a portion of the top of said casing, a concave receptacle in the remaining portion of said top, an indicia disposed in said casing obliquely with respect to the mirror, a support to hold the indicia in the aforesaid position, a U-shaped reflector having its bent portion secured to the bottom of the casing and its lower arm in the same plane as the indicia, a lamp in the bottom of the reflector, current supply means for said lamp, and current controlled means in the bottom of the receptacle to operate the lamp.

8. A coin holder comprising a casing, a translucent mirror and a concave receptacle in the top of said casing, an indicia disposed beneath said mirror and an electric lamp in front of the same in said casing,

current supply means for said lamp, a pair of spaced contacts in the receptacle, and connections between the same and lamp to operate said lamp.

- 5 9. A coin holder comprising a casing having a sloping top, a translucent mirror in the upper portion of the same and a concave receptacle in the lower, a removable base in said casing having therein an indicia
10 supported beneath the mirror, and an electric lamp and reflector in front of the same, clamps to hold a battery on said base, a pair of metal contacts in the bottom of the recep-

tacle, a connection between one terminal of the battery and the lamp, and connections 15 between one contact and the lamp and the other contact and other terminal of the battery.

In testimony whereof we affix our signatures in the presence of two witnesses.
